UNITED STATES PATENT OFFICE

ELLIOTT I. PETERSEN, OF ENFIELD, CONNECTICUT, ASSIGNOR TO BIGELOW-SANFORD CARPET CO., INC., OF THOMPSONVILLE, CONNECTICUT, A CORPORATION OF MASSACHUSETTS

LABEL

Application filed March 12, 1932. Serial No. 598,396.

This invention relates to floor coverings such for instance as pile carpets and rugs combined with an identifying marker or label.

5 Heretofore it has been the practice to mark the back of a rug or carpet with the desired information identifying the maker and the kind of fabric or other desired information. This practice is open to the serious objection 10 that it requires the floor covering to be turned or folded back whether the floor covering is exhibited singly or in piles upon the floor.

The present invention contemplates the combination of a pile floor covering such as 15 carpets or rugs and a flexible label or marker which projects from the edge of the floor covering and presents the identifying marks readily to an observer without the necessity for turning the floor covering bottom up.

20 In the broader aspects of the invention the pile carpet or rug is provided with a flexible label or marker secured to the edge portion thereof and extending freely therefrom, and since flexibility is a desirable attribute, the 25 marker or label is formed of textile material.

Floor coverings such as carpets and rugs are usually provided with a plain woven or unpiled head, and advantage is taken of this 30 fact in so combining the pile floor covering and label or marker, that the pile surface of the floor covering is not hidden by the marker or label.

In some cases it may be desirable to detach the projecting flexible label from the 35 floor covering after the latter has been sold but still maintain upon the back of the floor covering identifying information and the present invention therefore further contemplates that the flexible label shall have one of 40 its portions secured to the back of the floor covering sufficiently remote from the edge thereof that when the projecting portion of the flexible label has been removed, there still remains upon the back of the carpet or rug the 45 identifying information desired.

One of the important features of the present invention with respect to pile carpets and rugs consists in a double flexible label or marker formed of textile material and comprising an upper data bearing portion

and a lower portion united by a fold beyond the edge of the floor covering, and secured to the floor covering in non-interfering relation with the pile surface.

Since the textile flexible label or marker 55 is to extend freely beyond the edge of the floor covering it may be desirable at times to provide a stiffener extending outwardly from the edge of the floor covering between the two members of the label or marker. 60 Such stiffener is preferably of such a character that while it insures the projection of the marker or label outwardly beyond the edge of the floor covering it will nevertheless be not sufficiently rigid to interfere with 65 the general flexibility of the label itself.

The invention and novel features thereof will best be made clear from the following description and accompanying drawing of 70 one good form thereof.

In the drawing:—

Fig. 1 is a perspective view of a pile carpet or rug having the label of the present invention combined therewith;

Fig. 2 is a sectional view through the label 75 and carpet or rug of Fig. 1;

Fig. 3 is a perspective view looking at the bottom portion of the rug or carpet and showing a modification of the invention; 80

Fig. 4 is a view similar to Fig. 2 showing the modified form of the invention.

The floor covering, which as hereinbefore indicated, is of the pile carpet or rug type, comprises a ground fabric 1 having the upwardly projecting pile yarns 2 secured to the ground fabric. At the terminal end portion of the pile carpet or rug is a "head" or "heading" formed of plain woven ground fabric 3 and as shown, such heading 3 is 85 turned back to form a rounded edge portion 4 slightly beyond the pile surface of the carpet or rug.

In order that the maker's name or other desired information may be readily observable when the carpet or rug lies flat upon the floor or is stacked with others in a pile, the present invention contemplates that the marker or label 5 be formed of flexible material suitable to bear the desired data and 90

in the present instance of the invention the projecting portions of the label are formed of textile material, such for instance as a relatively wide strip of ribbon or the like, and that the material be bent or folded between the ends thereof to form an upper data bearing portion 6 and a lower portion 7, both of which are connected by the bend or fold 8 at a distance from the edge of the pile carpet or rug.

The lower portion 7 is preferably longer than the upper portion 6, as shown, and extends along the under face of the rug or carpet to form a data bearing portion 10, which may be permanently secured and remain upon the back of the carpet or rug when the projecting portion has been removed.

The upper data bearing portion 6 of the label or marker is secured to the edge of the carpet or rug at or slightly beyond the pile surface thereof and as shown in the present instance the upper portion 6 is secured to the rounded edge 4 of the heading by stitches or other securing means 9, while the lower data bearing portion 10 is permanently secured to the lower face of the carpet or rug by one or more rows of stitches or the like 11 and 12, the former passing through the turned over heading while the latter may conveniently be connected to the back of the ground fabric.

After the carpet or rug has been sold and is placed in use the projecting portion of the label or marker 5 may be removed by cutting the stitches or securing means 9 and severing the marker or label along the line 13, Fig. 3, the result being that the projecting portion of the label or marker is detached from the carpet or rug and from the permanent portion of the label or marker at the under face of the ground fabric.

It will be noted in Figs. 2 and 4 that the upper data bearing portion 6 on the label or marker where it is connected to the inturned heading extends upwardly towards the plane of the pile surface.

In Figs. 3 and 4 a slightly modified form of the label or marker is shown wherein the stiffener 14 extends between the upper and lower portion 6 and 7 respectively of the marker or label and serves the purpose of maintaining the label or marker in a flat and extended position from the edge of the pile carpet or rug without at the same time rendering the marker or label rigid. In other words, the stiffener 14 may be conveniently secured to the edge of the pile carpet or rug at the bend of the heading and extend therefrom between the upper and lower portions of the label or marker towards the bend 8 connecting the two.

The function of the stiffener 14 is not to lend undue rigidity to the label or marker but to keep it extended from the edge of the

carpet or rug and as shown in the present instance of the invention, the stiffener 14 may be formed of buckram, crinoline, hair cloth or the like, the free end portion of which extends towards but is not connected to the bend 8 joining the upper and lower portions 6 and 7 of the label or marker.

What is claimed is:

1. In combination with a floor covering comprising a ground fabric having a pile surface and a plain woven end folded under to form a folded head at the termination of the pile surface, a flexible label formed of flexible textile material having an upper and a lower portion united beyond the folded head, and means for securing the ends of the upper and lower portions of the label to the folded head in non-interfering relation with the pile surface.

2. In combination with a floor covering comprising a ground fabric having a pile surface and a plain woven end folded under to form a folded head at the termination of the pile surface, a flexible label formed of flexible textile material having an upper and a lower portion united beyond the folded head, means for securing the end of the upper portion of the label to the bend of the folded head in non-interfering relation with the pile surface, and means for securing the end of the lower portion of the label beneath the folded head.

In testimony whereof, I have signed my name to this specification.

ELLIOTT I. PETERSEN.
